Ch. Howdell

UNITED STATES PATENT OFFICE

FRANK L. M. GRANIER, OF RAYMOND, ILLINOIS.

HARNESS.

SPECIFICATION forming part of Letters Patent No. 363,818, dated May 31, 1887.

Application filed April 1, 1887. Serial No. 233,284. (No model.)

To all whom it may concern:

Be it known that I, FRANK L. M. GRANIER, a citizen of the United States, residing at Raymond, in the county of Montgomery and State 5 of Illinois, have invented a new and useful Improvement in Harness, of which the following is a specification.

My invention relates to an improvement in harness; and it consists in the novel construction and arrangement of the adjustable trace attachment and pad-loops, which will be more fully hereinafter described, and pointed out in the claims.

One object of my invention is to provide an 15 adjustable attachment in connection with the trace of harness whereby the same may be lengthened or shortened to fit different-sized horses without the use of buckles or tugs.

A further object of my invention is to provide a harness attachment in connection with the trace which renders said trace not only 20 readily adjustable, but at the same time of much more simple and effective construction, with a great saving in leather used in the 25 making.

A still further object of my invention is to construct the several parts forming my improvement in such a manner that they are readily applied in connection with the trace 30 without any alterations in the formation thereof, and without any unnecessary labor in the application, the said parts being strong and durable, easily handled and operated, readily understood, positive in their desired ultimate 35 result, and cheaply manufactured.

I attain these objects by the construction illustrated in the accompanying drawings, wherein like letters of reference indicate like parts in the several views, and in which—

40 Figure 1 is a perspective view of a portion of a trace, showing my improvements attached thereto, the said trace being of itself shown attached to a hame. Fig. 2 is a detailed view of the pad-loop. Fig. 3 is a detail perspective 45 view of the adjustable trace attachment.

A indicates a trace, the rear portion of which is provided with a series of apertures, a. To the rear portion of the trace is secured the adjustable trace attachment by means of an 50 attaching-loop, B, which is riveted to the said trace. The attachment consists, essentially,

of a spring-plate loop, C, which passes over the end of the trace, the one side of the said loop having a stud or pin, c, formed integrally therewith, which passes through the trace and through an aperture, c', in the outer end of the said loop. About midway of the outer portion of the plate C a wire spring, C', is secured at one end, the other end of the said spring passing up to the forward end of the said loop-plate C, and is provided with a hook, c'', on its forward end, which passes through the aperture c', formed in the stud c, extending upward from the bottom of the plate. By this means the said plate C is secured to the end of the 65 trace, the upper end of the said plate passing through and being confined by the attaching-loop B. The rear side of the plate may be covered with leather, so as not to rub the animal should that portion of the trace come in contact with him. An attaching-loop, D, is secured in the end of the loop-plate C, which may be attached to the thill or trace chain of the vehicle.

In adjusting the trace to different lengths by 75 this attachment the spring engaging with the stud c is released from the upper side of the plate C and disengaged from said stud, or the pin or stud may be drawn through said plate C by the rear portion thereof and moved into 80 engagement with any one of the other apertures a, as shown, in either direction, to lengthen or shorten the trace and adjust the same to the size of the animal in connection with which the harness is adapted to be used.

To adjust the collar a metallic adjusting-loop, E, is inserted and secured between the plies forming the trace, and thereby held in a stationary position. The upper side of the loop is provided with a series of two or more 90 smaller loops, e, which are adapted to be engaged by the strap in the lower end of the collar or pad, and as the harness is shortened or lengthened the collar must of necessity be changed from one loop to another. The 95 lower side of this loop is provided with an elongated loop, e', in which the holdback-strap is secured.

By the use of my improved attachment in connection with traces of harness the use of 100 hame-tugs is dispensed with, as also the use of buckles. The harness can be as readily ad-

justed when the animal is hitched as when the harness is removed from the animal. It can be adjusted from either side with rapidity, and the construction of the parts is such that they 5 will be capable of resisting heavy strain brought to bear thereupon. The wearing strain brought to bear upon the trace next to the cockeye is not as great as in the use of the form of trace heretofore used, and the said 10 trace will therefore be much more durable. The attaching end of the trace, being constructed of metal, is not so liable to rot as in the form of trace heretofore known and used. When the horses are harnessed to the vehicle, 15 it is not necessary to go between them to lengthen or shorten the trace, and four traces can be changed as quickly by the use of my attachment as one can now be done.

The novelty and utility of my device are evident, and its practicability will render it of indispensable need in the many forms of harness now in use, and, in view of its ready application, it does not increase the expense of the old form of trace.

25 It is obvious that many minor changes in construction and arrangement of the parts might be made and substituted for those shown and described without in the least departing from the nature and principle of my invention.

30 Having thus described my invention, I claim—

1. The combination, with the trace, of the adjustable pad-loop E, having a series of smaller loops, e, arranged on the upper side 35 thereof, by which the collar or harness-saddle may be adjusted, substantially as described.

2. The combination, with a trace, of an adjustable trace attachment consisting of a looped metallic spring-plate, C, having a stud 40 or pin, c, on its one side, passing through ap-

ertures in the trace and plate, and secured by a wire spring, C', attached to the outer side of said metallic plate, substantially as described.

3. The combination, with the trace, of an adjustable metallic spring-plate secured to said 45 trace by means of a loop, B, a stud or pin, c, secured to one side of said metallic looped plate and passing through the trace and the other side of the plate, and a wire spring, C', secured to the looped plate at one end and engaging the apertured end of the stud or pin at its free end, substantially as described.

4. A trace attachment adjustable on the trace, consisting of a metallic looped plate engaging with each side of the trace, having a 55 stud secured at one end passing through the trace and through an aperture in the other end of said plate, a securing-loop, B, for attaching the metallic plate to the trace, and a wire spring engaging with the apertured end of the 60 adjusting pin or stud, and adapted to release the said attachment entire from connection with the trace and allow it to be adjusted to lengthen or shorten the said trace, substantially as described.

65 5. A trace comprising an adjusting pad-loop, E, provided with a series of smaller loops, e, and an adjustable spring looped plate, C, engaging with the end of the trace, whereby the harness-saddle and the trace may be adjusted and regulated for use in connection with horses of varying sizes, substantially as described.

In testimony that I claim the foregoing as my own I have hereto affixed my signature in 75 presence of two witnesses.

FRANK L. M. GRANIER.
